UNITED STATES PATENT OFFICE.

ALMON G. WARD, OF WARREN, OHIO, ASSIGNOR TO THE DAY-WARD COMPANY, OF SAME PLACE.

DESIGN FOR A BATH-TUB.

SPECIFICATION forming part of Design No. 26,929, dated April 20, 1897.

Application filed January 30, 1897. Serial No. 621,365. Term of patent 14 years.

To all whom it may concern:

Be it known that I, ALMON G. WARD, a citizen of the United States, residing at Warren, in the county of Trumbull and State of Ohio, have invented and produced a new and original Design for Bath-Tubs, of which the following is a specification, reference being had to the accompanying drawings, showing a part thereof.

10 In the drawings, Figure 1 is a side elevation of my new and useful design for bath-tubs; and Fig. 2 is a cross-section thereof on line *x x*, looking to the left.

The design consists in the shape and configuration of the tub as shown, provided with a natural-wood finish and decoration of the body of the tub and the ornamental supports near its ends, the whole presenting an appearance and finish exceptional in the art.

20 A represents the central portion of the body of the tub, B the practically straight foot portion or section thereof, and C the inclined head portion or section. These three several sections or subdivisions of the tub are defined and separated as to one another by ornamental upright borders D and E, which stand out in plain relief from the adjacent surfaces and extend from beneath the bottom to the upper edge of the tub, where they

meet the rounded top rim or border G. The 30 front border D is further distinguished by an ornamental projection *d* at the bottom of the tub.

The surface of the sections A, B, and C constitute together the exposed outer surface of 35 the body of the tub, which is marked by a highly-polished and ornamental natural-wood finish. Then to deepen the effect of this natural-wood finish and appearance I decorate the top edge thereof all around with an attractive 40 rim or band G of the same kind and color of wood and relieve the edge between these wood surfaces with a beaded finish 2, especially at the ends of the tub. Interiorly the tub has a plain, highly-polished, and lustrous appearance, such as porcelain, bright tin, or the like would afford, and is in striking contrast with 45 the exterior of the tub.

What I claim is—

The design for a bath-tub substantially as 50 shown and described.

Witness my hand to the foregoing specification this 1st day of January, 1897.

ALMON G. WARD.
